United States Patent Office

Des. 225,098
Patented Nov. 14, 1972

225,098

DISPLAY BOX

Robert J. Mulligan, Wheaton, Ill., assignor to Richardson-Merrell Inc., New York, N.Y.

Filed Oct. 27, 1970, Ser. No. 25,682

Term of patent 14 years

Int. Cl. D9—03

U.S. Cl. D9—235

FIG. 1

FIG. 2

FIG. 3

FIG. 4

FIG. 5

FIG. 1 is a top plan view of a display box showing my new design, the bottom being substantially identical thereto;

FIG. 2 is an end elevational view;

FIG. 3 is a front elevational view;

FIG. 4 is a rear elevational view; and

FIG. 5 is a top plan view of the interior of the display box in a fully open condition.

I claim:

The ornamental design for a display box, substantially as shown and described.
